TEMPERATURE COMPENSATED SHOCK RESISTANT FUSE

Herbert W. Houston and John E. Urbany, Los Angeles, Calif., and Donald K. Allison, Albuquerque, N. Mex., assignors to the United States of America as represented by the Secretary of the Army

Application June 3, 1948, Serial No. 30,864

8 Claims. (Cl. 102—70)

This invention relates to an atmospheric pressure responsive fuse, and is designed to provide a fuse for detonating an explosive charge, particularly an aerial bomb. The fuse functions automatically when the charge attains a determined altitude. The invention provides alternative operating mechanisms for operation on ascent and descent of the charge. It also provides shock-resistant means to prevent accidental functioning of the fuse due to vibration or impact. There is also provided compensation means to counteract atmospheric pressure variations due to temperature variations. The particularly novel features of the fuse are the sectional case for enclosing and supporting the operative mechanism, the restraining means for releasably latching the firing means, the pressure operated means for releasing the restraining means, the shock-resistant means to prevent accidental release of the restraining means, and the compensation means responsive to temperature variations.

While there have been illustrated in the drawings filed herewith and hereinafter fully described several specific embodiments of the invention, it is to be distinctly understood that the invention is not considered to be limited to said specific embodiments and that its scope is defined by the claims appended hereto.

In the drawings:

Fig. 1 is a side elevation of the fuse and charge, partly in section;

Fig. 2 is a vertical section on the line 2—2 of Fig. 1, in the direction of the arrows;

Fig. 3 is a vertical section on the line 3—3 of Fig. 2, in the direction of the arrows;

Figures 4 through 8 are sectional views in planes perpendicular to the longitudinal axis of the instrument as indicated by the lines 4—4; 5—5; 6—6; 7—7 and 8—8, respectively, of Figure 2.

Fig. 9 is a fragmentary vertical section, similar to the upper portion of Fig. 3, showing the thermostatic adjusting elements modified by elevation of temperature;

Fig. 10 is a vertical section similar to Fig. 3 showing a modified form of the fuse;

Fig. 11 is a fragmentary vertical section of another modified form of the fuse;

Fig. 12 is a detail view of one of the dogs of the latching means;

Fig. 13 is a detail view of the firing pin.

As illustrated in the drawings, the fuse has a tubular case for enclosing and supporting the operating mechanism, and comprising five, cylindrical, co-axial elements inter-engaged in lapped joints for facilitating assembly and cemented together by suitable means when assembled. A cap 1 for closing the top of the case is seated on an element 2 and has a neck 3 projecting downwardly into the upper end of element 2 and suitably axially spaced relative to an interior peripheral flange 4 of element 2 to secure the rim of a flexible element 63 therebetween. Element 2 is seated on an element 5 which has a neck 6 projecting upwardly into the lower end of element 2. Element

2

5 is seated on an element 7 which has a neck 8 projecting upwardly into the lower end of element 5 and suitably axially spaced relative to an interior peripheral shoulder 9 on element 5 to clamp the rim of a flexible diaphragm 14. Element 7 is seated on an element 10 and has a neck 11 which projects downwardly into the upper end of element 10. Element 10 has a longitudinal key 10-a received in key-way 11-a in neck 11 to prevent relative rotation of elements 7 and 10. The lower end of neck 10 10 11 is spaced from a peripheral shoulder 12 on element 10 to clamp a circular disc 24. Element 10 has an exterior peripheral groove 13 to receive the adjacent end of a container 44.

Between the neck 8 of the element 7 and the shoulder 15 9 of the element 5, there is mounted a circular, concave-convex flexible diaphragm 14, of any suitable material, such as rubber, having a peripheral flange 15 configured to be engaged by the co-acting faces of neck 8 and shoulder 9 when the element 5 is seated on the element 7. The 20 diaphragm 14 is so mounted in the case as to effect a gas-tight joint therewith. The diaphragm 14 has a central, thickened and bored portion 16 on which is mounted a plate 17 supporting a clevis 18, and having a threaded bolt 19 passed through the diaphragm 14 and a plate 20, and provided with a nut 21 for clamping the diaphragm 14 between plates 17 and 20 in a gas-tight joint therewith. The plate 20 has formed integral therewith a depending cage 22 having on its lower end a latch 23 in the form of a ring coaxial with diaphragm 14.

Between the neck 11 of the element 7 and the shoulder 12 of the element 10, there is mounted a circular disc 24 clamped securely in position when the element 7 is seated on the element 10. Disc 24 has a central bore 25 and a pair of upstanding lugs 26 at the sides of bore 25, respectively, in which are pivoted a pair of dogs 27 in the upper ends of which are journaled rollers 28. Slidably received in the bore 25 there is a firing pin 29 having a peripheral bevel 30 on its upper end and a peripheral groove 31 adjacent thereto having upper and lower bevelled cam faces 32 and 33. Dogs 27 have bevelled noses 34 intruded into groove 31 and engaging face 32 of firing pin 29 when the dogs 27 are relatively proximately disposed by the rollers 28 latched by the circumscribing ring 23, as shown in Fig. 3. The pin 29 has a second peripheral groove 35 inferior to groove 31. Formed integrally with the disc 24, there is a tubular housing 36, coaxial with disc 24, and into which depends the firing pin 29 which has on its lower end a peripheral flange 37. A coil spring 38 about pin 29 is confined between disc 24 and flange 37, biasing pin 29 downwardly. Pin 29 has, on its lower extremity, a detonating point 39. Threaded on the lower end of housing 36 is a casing 40 in which is mounted a primer 41 for a booster charge 42 in casing 40. Booster charge 42 is disposed in a main explosive charge 43 for the firing of which the novel fuse is designed, and which is packaged in a container 44, the open neck 45 of which is seated in groove 13 of element 10 of the case of the fuse, lashing 46 serving to unite the case and container 44.

Carried on the upper end of the neck 6 of the element 5 of the case there is a spider 47 (see Figure 5) having convex ends 48 seated against the element 2, and depending lugs 49 in which are pivoted a pair of bell cranks 50 having forked ends 51, embracing pin 52 in clevis 18, and arms 53 carrying inertia masses 54. Mounted on the spider 47 by bolts 55, there is a V-shaped, bimetallic, thermostatic member 56 comprising two arms 57 and 58 extending upwardly in element 2 of the case. Arm 58 is provided on its upper end with a bracket 59 supporting a second V-shaped, bimetallic, thermostatic member 60 comprising two arms 61 and 62, arm 61 being attached to bracket 59. As shown in Fig. 3, the members 56 and 60 are so dimensioned and related,

60 65 70

that member 56 comprehends member 60, the arms 57, 58, 61 and 62 being normally parallel.

Between the neck 3 of the cap 1 of the case and the flange 4 of the element 2, there is mounted a circular flexible diaphragm 63 of material such as rubber having a peripheral flange 64 configured to be engaged by the co-acting faces of neck 3 and flange 4 when the cap 1 is seated on the element 2. The diaphragm 63 is so mounted in the case as to effect a gas-tight joint therewith.

The diaphragm 63 is formed as a frusto-conical member having a central, thickened and bored portion 65 to which is fastened a plate 66 having a threaded bolt 67 passed through portion 65 and a washer 68 thereon and provided with a nut 69 for clamping the diaphragm 63 between plate 66 and washer 68 in a gas-tight joint therewith. The plate 66 is provided with depending lugs 70 (see Figure 3) in which is pivoted one arm of a bell crank 71, the other arm of which is pivoted to a link 72 pivotally mounted on a bail 73 mounted in arm 57 of the thermostatic member 56. Bell crank 71 is pivoted intermediate its arms to one arm of a second bell crank 74 which is received in the slotted upper end of arm 57 and pivoted on a bail 75 mounted in arm 57. The other arm of bell crank 74 is pivoted to a link 76 pivoted on a bracket 77 mounted on the upper end of arm 62 of the thermostatic member 60.

As shown in Figs. 3 and 9, when the parts are assembled as described, the diaphragm 63 is dished, its degree of deformation depending upon the position of plate 66 determined by the positions of the thermostatic arms 57 and 62 and their associated linkage.

Cap 1 has an orifice 78 to provide communication for the interior of cap 1 with atmosphere.

The element 2 has an orifice 79 (Figures 2 and 4) to provide communication for the interior of the casing between the diaphragms 14 and 63. Snugly fitted in the orifice 79, there is a nipple 80 of a plug 81 having a threaded bore 82 in which is threaded a bolt 83 with a slotted head 84 seated in recess 85 of plug 81. The slotted head 84 seated in recess 85 and the bore 82 are co-axial. Nipple 80, the recess 85 and the bore 82 are co-axial. Bolt 83 has a central bore 86 with which connects a radial bore 87 opening through the periphery of bolt 83 to its end adjacent head 84. The parts are so designed and related that when the bolt 83 is set up in plug 81 so that head 84 is seated in recess 85, the bore 87 is closed to seal that portion of the interior of the casing between diaphragms 14 and 63, and the head 84 is disposed interiorly of the periphery of element 2, and that when bolt 83, unscrewed by turning head 84 with a suitable tool, is retracted sufficiently to withdraw bore 87 from bore 82 and into recess 85, and head 84 is exterior of the periphery of element 2, the bores 86 and 87 afford communication for the interior of the casing to atmosphere.

The element 10 and neck 11 of the element 7 have co-axial transverse orifices 88 and 89. Figure 8, in which is slidably disposed a safety pin 90 which is passed through orifices 91 so disposed in lugs 26 on disc 24 as to pass pin 90 through groove 35 in firing pin 29. The safety pin 90 has an arm 92 normal to pin 90 and exterior of the periphery of the case (Figs. 1, 3 and 8).

The element 7 has a pair of relatively spaced transverse parallelly disposed orifices 93 and sockets 94 co-axial with orifices 93, respectively. A hairpin detent 95 has its legs 96 slidable through orifices 93, and their ends seated in sockets 94. Orifices 93 and sockets 94 are so disposed as to position the legs 96 about the dogs 27 when the dogs 27 are disposed in ring 23. The bight 97 of detent 95, connecting the legs 96, has swingable thereon a tongue or strap 98 received against the periphery of the case when the detent 95 is mounted in the case, and confined by a ring 99 slidably on the case. It will be noted (Fig. 1) that the arm 92 of safety pin 90 is confined by the detent 95, so that detent 95 must

be removed to permit removal of pin 90, and (Fig. 2) that ring 99 is disposed over orifice 79 when positioned to confine tongue 98.

In Fig. 10, there is shown a modified form of the fuse 5 in which the thermostatic members, flexible diaphragm and linkage therefor are eliminated. In this form of the device, the element 2 has an inner peripheral flange 4-a spaced from the lower end of neck 3 of cap 1. Between neck 3 and flange 4-a, there is mounted a partition 100 in a gas-tight joint therewith and forming the upper 10 end of the chamber in the casing extending from the diaphragm 14 to partition 100. Partition 100 has a central boss 101 projecting upwardly and a socket 102 on its lower side in which is seated, in a gas-tight joint, 15 a capillary tube 103 having a minute bore 104. The boss 101 has a minute bore 105 connecting socket 102 with the interior of cap 1. Except for the above-described elements the form of the device shown in Fig. 10 is identical with the form shown in Figs. 1 to 9.

In Fig. 11, there is shown a modified form of the device 20 in which a flexible diaphragm 14-a is designed to flex upwardly to raise the latch 23. In this form, a shoulder 9-a of an element 5-a is seated on neck 8 of the element 7 and the peripheral flange 15-a of the diaphragm 14-a is seated on a shoulder 9-b of the element 5-a. A sleeve 6-a, fitted in the upper end of element 5-a and projecting therefrom, is seated on flange 15-a. Element 2-a is fitted about the projecting portion of sleeve 6-a and is seated 25 on the element 5-a. The sleeve 6-a comprises two semi-cylindrical portions for a purpose presently explained. The spider 47 is mounted on the top of sleeve 6-a and has lugs 49-a somewhat longer than the lugs 49 of the form shown in Figs. 1 to 9. On lugs 49-a, there are pivoted two bell cranks 50-a, which are reversely disposed relative to clevis 18 from the disposition of bell cranks 50, to prevent accidental raising of the ring 23. Other parts of 30 this form of the fuse are identical with corresponding parts of the form shown in Figs. 1 to 9.

The method of assembling the above-described parts 35 will now be explained. The thermostatic member 56 with member 60 and the linkage mounted thereon is mounted on the spider 47. The bell cranks 50 are mounted on lugs 49 of the spider 47, and pin 52 passed through clevis 18 and forked ends 51 of cranks 50, attaching clevis 18, plate 17 and bolt 19 under spider 47. Spider 47 is then seated on neck 6 of element 5. The diaphragm 14 is then mounted on bolt 19 and cage 23 is mounted on bolt 19, the parts being properly related by setting up nut 21 on bolt 19, and the flange 15 of diaphragm 14 being seated on shoulder 9 of element 5. Element 2, with plug 81 40 mounted therein, is then seated on element 5, the ends 48 of spider 47 as well as neck 6 of element 5 and the lower end of element 2 being properly cemented to form a gas-tight joint. The flexible diaphragm 63 is mounted on plate 66 of the linkage on thermostatic member 56 and its flange 64 seated on flange 4 of element 2. Cap 1 is applied to upper end of element 2, its neck 3 engaging the flange 64, and the parts cemented to form a gas-tight joint.

The dogs 27 are mounted on lugs 26 of disc 24 which is then seated on neck 11 of element 7 and cemented thereto. Detent 95 is then inserted into element 7 embracing dogs 27. Pin 29 with spring 38 thereon is inserted through housing 36 and bore 25, spring 38 seating on lower surface of disc 24 in the inner end of housing 36. Pin 29 is forced inwardly sufficiently to cause bight 30 to 'cam' dogs 27 against legs 96 of detent 95 to admit pin 29 therebetween and to align groove 31 with noses 34 and groove 35 with orifice 89 in neck 11 and orifices 91 in lugs 26. Safety pin 90 is then temporarily inserted to hold pin 29 in adjusted position. Element 7 is then applied to element 5, neck 8 engaging flange 15 of diaphragm 14, and the parts are cemented to form a gas-tight joint. Application of element 7 to element 5 moves dogs 27 into latch ring 70 23. It will be noted (Fig. 3) that when dogs 27 are em- 75

braced by detent 95 and pin 29 is held by pin 90, the noses 34 engage the upper edge of cam face 32 and rollers 28 are sufficiently proximate for ring 23 to embrace them slightly above their axes. It is obvious that as dogs 27 are moved into adjusted position by seating element 7, the rollers 28 rotate as their axes become aligned with the transverse axis of ring 23, and that dogs 27 are moved away from legs 96 of detent 95 and toward pin 29 which causes noses 34 to cam upwardly pin 29 sufficiently to free pin 90 which is then removed. Element 10 is then applied to element 7, key 10-a seating in key-way 11-a and shoulder 12 bearing on the disc 24.

Detent 95 is removed, pin 90 is inserted and detent 95 replaced, engaging arm 92 of pin 90 (Fig. 1). Bolt 83 is threaded in bore 82 of plug 81 sufficiently for its head 84 to be received in recess 85.

Ring 99 is placed about element 2 to confine tongue 98 of detent 95. Casing 40 with detonator 41 and booster charge 42 may be threaded on outer end of housing 36 immediately prior to applying the fuse to the explosive charge.

In assembling the form of the fuse shown in Fig. 10, after element 2 has been seated on the element 5, the partition 100 is seated on the flange 4-a of element 2. The tube 103, which had been mounted in socket 102 in boss 101 of partition 100 before partition 100 is seated on flange 4-a, is disposed within element 2. When thus assembled the parts are cemented to form a gas-tight joint. Cap 1 is then applied to upper end of element 2, the neck 3 of cap 1 bearing on the partition 100, and the parts are cemented.

The method of assembling the form of the fuse shown in Fig. 11 will now be explained.

When the dogs 27 have been assembled with pin 29 on disc 24 and in element 7, as above described, element 5-a is mounted on the element 7. Latch ring 23, diaphragm 14-a and clevis 18 are then assembled by setting up nut 21 on bolt 19. Ring 23 is then moved downwardly by pressure on clevis 18 and bolt 19 until dogs 27 are disposed as shown in Fig. 11, and flange 15-a of diaphragm 14-a is seated on shoulder 9-b of element 5-a. One of the semi-cylindrical portions of the sleeve 6-a is then mounted in the element 5-a and on flange 15-a, to support the spider 47 which is then mounted thereon so that clevis 18 is disposed between lugs 49-a. Bell cranks 50-a are then applied to clevis 18 and pivoted in lugs 49-a. It is to be understood that the portion of sleeve 6-a, previously mounted, is so disposed as to afford access between diaphragm 14-a and spider 47 to permit mounting bell cranks 50-a. The other portion of sleeve 6-a is then mounted in element 5-a and on flange 15-a, and element 2-a is disposed about the upper end of sleeve 6-a and seated on element 5-a the parts being cemented to form a gas-tight joint. It is to be understood that before the spider 47 is mounted on sleeve 6-a, the thermostatic element 56 and its associated parts are mounted on the spider 47. The remainder of the assembling is as previously described.

From the foregoing description of the details of construction of the fuse, its use and operation can be understood. The operation of the form of the fuse shown in Figs. 1 to 9 will now be described. This form of the fuse is designed to function on reduction of atmospheric pressure viz. on ascent. With parts assembled as shown in Figs. 1 to 8, the fuse is conditioned for use. Before the fuse is connected with container 44, ring 99 is moved upwardly on the case, off of orifice 79 and tongue 98, and hair-pin detent 95 is withdrawn, releasing safety pin 90. It will be noted (Fig. 3) that when the dogs 27 are embraced by latch 23, both legs 96 and pin 90 are free for unobstructed withdrawal. However, should the operative parts have become accidentally displaced so that dogs 27 are not held in latched position by ring 23, the dogs 27 will bear against legs 96 to impede their withdrawal and that when legs 96 are withdrawn, the dogs 27 cammed

out of groove 31 by upper cam face 32 will release firing pin 29 which is projected by its spring 38 to engage safety pin 90 in groove 35, thereby impeding removal of pin 90. Should it be found that pin 90 is not freely withdrawable, 5 the fuse is shown to be in unusable condition and cannot be used, until firing pin 29 is re-cocked. When the parts are properly disposed, pin 90 can be readily withdrawn. After the detent 95 has been removed, safety pin 90 is 10 allowed to remain in place as a precaution to prevent accidental release of firing pin 29. The bolt 83 is then screwed out sufficiently to put the chamber between diaphragms 14 and 63 in communication with atmosphere through bores 86 and 87, the chamber being otherwise sealed. It will be noted that withdrawal of hairpin detent 95 opens ori- 15 fices 93 through which the chamber between diaphragm 14 and disc 24 is put in communication with atmosphere. Thus it is obvious that diaphragm 14 is subjected to uniform atmospheric pressure on both sides and is thereby immobilized. When the device is at that altitude 20 at which the desired atmospheric pressure obtains for charging the chamber between diaphragms 14 and 63, the bolt 83 is set up in plug 81 to close bore 87, thus completely sealing the chamber between diaphragms 14 and 63. The fuse is then attached to the charged container 25 44 and safety pin 90 is withdrawn. The fuse is now armed and ready to function. When the device is ele- 30 vated, above the altitude at which it is armed, to that altitude at which the atmosphere pressure is sufficiently reduced below that of the pressure in the upper chamber, the diaphragm 14 is deformed, since the chamber below diaphragm 14 is charged through orifices 88, 89 and 93 with the atmosphere of reduced pressure. It is to be understood that the parts are constructed and related so that at that point in ascent of the device at which the 35 pressure differential reaches the desired amount, the dia- 40 phragm 14 will be flexed downwardly out of its normally upwardly curved position to depress ring 23 sufficiently to pass below the axes of the rollers 28 which are pressed outwardly by action of spring 38 and cam surface 32 on 45 noses 34 of dogs 27, tending to force ring 23 downwardly sufficiently to release dogs 27 from pin 29 which is projected downwardly by spring 38 through tube 36, its point 39 striking detonator 41 firing booster charge 42 and exploding charge 43.

It will be noted (Figs. 2 and 3) that as the diaphragm 14 is normally curved upwardly and cannot be moved further upwardly and the ring 23 is so related to diaphragm 14 as to latch dogs 27 when diaphragm 14 is normally curved upwardly, the ring 23 cannot be moved upwardly to release the dogs 27. There is, therefore, no need for 50 means to prevent accidental lifting of ring 23. However, since the fuse functions by flexing of the diaphragm 14 downwardly to depress the ring 23 to release the dogs 27, the device is provided with means to prevent accidental flexing of the diaphragm 14 downwardly, as by vibration to which the device may be subjected. The inertia masses 55 54 are so connected to the flexible structure by the crank arms 53 as to counteract any tendency of the diaphragm 14 and ring 23 to move downwardly, since any impulse by 60 vibration tending to move the diaphragm 14 and ring 23 downwardly tends to move masses 54 downwardly which, through crank arms 53, tend to move diaphragm 14 and ring 23 upwardly.

In the foregoing description of the fuse it was explained 65 that the fuse functions when the differential of the pressures on the opposite sides of diaphragm 14 reaches the desired amount. It is obvious, therefore, that for the desired proper functioning of the fuse the pressure in the sealed chamber must be maintained uniform. Since the mass of atmosphere in the sealed chamber is subject to pressure variations incident to temperature variations, the device is provided with thermostatic automatic means for varying the volumetric capacity of the sealed chamber to maintain uniformity of pressure of the mass of atmosphere sealed therein. In the form of the device shown in Figs.

1 to 9, this means comprises the thermostatic members 56 and 60, the flexible diaphragm 63 and the linkage therefor. As clearly shown in Fig. 9, when the temperature in the sealed chamber is elevated to a degree to increase the pressure of the atmosphere in the chamber due to its expansion by heating, the arms 57 and 58 of the thermostatic member 56 are caused to move apart, and the arms 61 and 62 of the member 60 move likewise. Since member 60 is movable bodily with arm 58, the movement of arm 62 is augmented. The deflection of arm 57 moves bell-crank 74 bodily relative to the axis of bolt 67 in the center of diaphragm 63, and consequently moves bell-crank 71 likewise, tending to lift diaphragm 63. Simultaneously this movement of arm 57 causes link 72 to rock crank-arm 71, tending to lift diaphragm 63. Simultaneously, the movement of arm 62 causes link 76 to rock bellcrank 74 raising bell-crank 71 bodily, tending to lift diaphragm 63. It is obvious that this raising of diaphragm 63, increasing the volumetric capacity of the chamber, compensates the expansion to maintain the desired pressure in the chamber. It is obvious that the reverse movements are produced by reduction of temperature causing reduction of pressure due to contraction by cooling.

As above pointed out, in the form of the device shown in Fig. 10, the thermostatic compensating means is eliminated. This form of the device is provided with the capillary tube 103 to provide means to maintain constant pressure of the atmosphere in the sealed chamber. Increased temperature in the sealed chamber, causing expansion of the atmosphere produces evacuation of that portion of the atmosphere, through tube 103, to compensate the expansion to maintain uniform pressure on diaphragm 14. Reverse operation, on cooling, effects the desired result. It is obvious that the cross-sectional area of bore 104 and length of tube 103 are designed to effect the above described results. Since the compensations by this means are effected at determined speeds, it is to be understood that the functioning of this form of the fuse is directly affected by the rate-of-climb whereby the pressure differential is effected. Should the speed of ascent of the device be considerably accelerated, the degree of compensation is consequently reduced, and compensation is increased at reduced rate of speed.

As above pointed out, in the form of the fuse shown in Fig. 11, the flexible diaphragm 14-a is designed to flex upwardly and it is obvious that in this form of the device the diaphragm 14-a is flexed by the pressure exerted by the atmosphere in the chamber below diaphragm 14-a when it becomes superior to the pressure in the sealed chamber above the diaphragm 14-a, the device functioning on descent. It is to be understood that the compensating means shown in Figs. 3 and 10 can be used alternatively with either of the forms of the fuse shown in Figs. 3 and 11.

We claim:

4. In a fuse for detonating an explosive charge, the combination of a tubular case, a transverse closure sealing one end of said case; a flexible transverse sealing wall intermediate the ends of said case dividing said case into first and second co-axial chambers, said case having an orifice therein providing a single port for the first of said chambers between said closure and said wall, and a plurality of orifices therein providing a plurality of ports for the second of said chambers; a removable closure for sealing said orifice providing said single port; a transverse closure for the other end of said case, and spaced from said wall to define said second chamber; firing pin means for detonating the charge, said firing pin means being supported on said second closure, means biasing said firing pin means to firing position; a dog mounted in said second chamber and pivotable from a first position engaging and holding said firing pin means against movement to firing position, and a second position releasing said firing pin means, and a latch ring connected with said sealing wall,

5 said latch ring normally engaging said dog to hold the same in first position and movable with said sealing wall in response to a change in differential pressure within and without said first chamber, to release said dog.

2. In a pressure-differential-responsive fuse, a tubular casing, walls closing the respective ends of said casing, a flexible diaphragm across said casing between said walls and dividing said casing into first and second chambers, a firing pin reciprocably mounted in the end wall of one said chamber, spring means urging said pin into firing movement, a dog operable in a first position to hold said pin retracted against the action of said spring means, means connected with said diaphragm and engageable with said dog in an undeflected position of said diaphragm to hold said dog in first position and movable with said diaphragm in response to a predetermined pressure differential between said chambers to release said dog, valve means operable to selectively connect one said chamber with the atmosphere, and means including a temperature-responsive element in said last-named chamber to vary the volume thereof directly with temperature to thereby maintain constant the pressure in said last-named chamber.

3. In a pressure-differential-responsive fuse, a tubular casing, first and second walls closing the respective ends of said casing, a flexible gas-tight diaphragm in said casing and, with said walls, dividing said casing into first and second chambers, a firing pin axially mounted in said second wall for movement from a retracted position to firing position, a spring urging said firing pin into firing position, a plurality of dogs mounted on said second wall about said firing pin, for pivotal movement in respective radial planes from a first position engaging and holding said firing pin in retracted position to a second position releasing said pin, a ring secured to said diaphragm and normally surrounding and holding said dogs in first position and moved by and with said diaphragm in response to a predetermined pressure differential between said chambers to free said dogs and release said pin for firing movement, and a capillary tube in said first chamber connecting the interior thereof with the ambient atmosphere.

4. In a pressure-differential actuated fuse, a tubular casing, first and second walls closing respective ends of said casing, a flexible gas-tight diaphragm in said casing and, in cooperation with said walls, dividing said casing into first and second chambers, a firing pin axially slidable in and through said second wall from a retracted to a firing position, spring means urging said pin into firing position, a plurality of dogs carried by said second wall and pivotable from a first position engaging and holding said pin retracted, to a second position freeing said pin for firing movement, safety means carried by said diaphragm engaging and holding all said dogs in first position when said diaphragm is undeflected, said safety means being moved by said diaphragm to release said dogs when said diaphragm is deflected in response to a predetermined pressure difference between said chambers, and a lever arm weighted at one end and connected with said diaphragm at the other, whereby to oppose movement of said diaphragm otherwise caused by shocks and jars.

5. In a pressure-differential responsive fuse, a closed 60 casing, a partition in said casing comprising a flexible gas-tight diaphragm dividing said casing into first and second chambers, a firing pin slidably mounted in said second chamber from a retracted to a firing position, spring means urging said pin into firing position, a plurality of dogs mounted about said pin for pivotal movement in respective planes radially of said pin from a first position engaging and holding said pin retracted, to a second position releasing said pin for firing movement, a ring secured to said diaphragm, said ring engaging said dogs to hold the same in first position when said diaphragm is in undeflected position and movable with said diaphragm to release said dogs in response to a predetermined pressure differential between said chambers, and valve means operable to selectively open or 70 close said first chamber to the ambient atmosphere.

6. A fuse as recited in claim 5, a second flexible diaphragm in the wall of said first chamber, and bimetallic thermostatic means in said first chamber and connected with said second diaphragm to flex the same in response to temperature changes in said first chamber and thereby maintain substantially constant the pressure therein. 5

7. A fuse as recited in claim 5, said dogs being two in number and on diametrically opposite sides of said firing pin, a first U-shaped safety pin with its bight portion outside said casing and its legs extending through apertures in said casing to engage and hold respective dogs in first position, a second safety pin extending through an aperture in said casing and engaging and holding said firing pin retracted, said second safety pin 15 having a bent end normally held between said casing and bight portion of said first safety pin.

8. A fuse as recited in claim 7, a tongue having one end secured to said bight portion, and a band encircling said casing and simultaneously holding said tongue against said casing and sealing off communication between said valve means and the ambient atmosphere.
